MAIL-MARKING APPARATUS

Application filed March 13, 1928. Serial No. 261,233.

This invention relates to improvements in a machine utilizing a die for stamping or imprinting indicia on matter which is passed through the machine or by the die. 5 The invention is especially adapted for use in connection with mail marking machines, such as those used for canceling stamps on letters.

In machines of the class above referred 10 to, the mail matter is first deposited on a feed table and after being separated by hand or some mechanical means constituting a part of the machine, it is brought by suitable feed rollers into cooperative position with the die used for canceling the stamp or making other indicia on the envelope or the like.

Heretofore it has been the practice on 15 such machines to rely on the feed rollers for passing the pieces of mail matter forward so as to actuate the trip mechanism for bringing the die into action and for moving the mail matter between the die and the pressure roller associated with the die.

20 It is the object of our present invention to improve the means for guiding and passing the mail matter between the pressure roller and the die whereby a more positive passage of the mail matter through the machine can be secured. Other ancillary objects will be apparent to one skilled in this particular art after a study of the specification in connection with the annexed drawings wherein—

25 Figure 1 is a side elevation of one form of machine which we have taken to illustrate the application of our invention.

Figure 2 is a sectional view through the die and its cooperating pressure roller.

30 Figure 3 is a section on a line 3—3 of Figure 2.

Figure 4 is a view of the clutch portion of the die structure taken at right angles to the view shown in Figure 2 and with certain of the parts broken away to show the interior construction.

45 Figure 5 is a fragmentary view of a modified form of means for holding the combined clutch cover and pulley in position.

50 Referring now to the details wherein like

numbers refer to the corresponding parts in the different views:

1 is the base of a small hand-power machine which for the sake of simplicity, we have chosen to show how our invention may be utilized. Such machines are especially suited for use in small post offices, but in larger post offices the machines are driven by a small motor, and it is of course understood that our invention is applicable to any such machines or other machines where-in the improved arrangement may be found useful. Base 1 carries a frame work 2 and a wheel 3 supported on shaft 4, which wheel is adapted to be operated by hand. The feed table 5 has a feed roller 6 for feeding the mail matter forward to the separator roller 7 which operates through a slot in a guard 8. The position of the separator roller 7 is adjusted by means of adjusting nut 9. The usual trip feed rollers 10 and 11 are provided; also a trip lever 12 which actuates a stop arm 13 carrying a stop roller 14. The stop roller 14 engages a corresponding roller 16 on a portion of the die structure 17.

55 The die shaft 18 has its bearings on a gear plate 19 and a trip post 20. Associated with the die is an ink roller 21 carried by an adjustable bracket 22. Positioned adjacent the die is a pressure roller 23, the surface of which is usually of soft rubber for the purpose of making good frictional contact with the mail matter. If further information is needed as to the operation of these parts, 60 this may be found in Jahn Patent 856,845, issued June 11, 1907.

65 Associated with the machine is a stacker 24 for receiving the letters after they have been stamped by the die on passage between the die and the pressure roller.

70 Our improvement resides particularly in the combination and cooperation between the pressure roller 23 and the die 17, and will be best understood by reference to Figures 2 to 95 5 inclusive. By referring to Figure 2, it will be seen that the pressure roller 23 is carried on a spindle 25 positioned in a bushing 28 carried by an arm 27 and driven by a gear 26. 15 Figure 3 illustrates a part of the housing of the 100

machine. The shaft 18 is continuously driven when the machine is in operation by a gear 29. Positioned on the shaft or spindle 18 is a clutch cup 30 having a hub 31 extending downward and fastened to the shaft 18 as by a pin 32.

Positioned within the cup is a disc 33 which is fastened to the cup 30 by a pin 34. At opposite points in the walls of the cup member 30 there is a slot for receiving arms 35 and 36. The lower ends of these arms are carried on a pin 37 which passes through a slot 38 in the hub 31. The upper ends of the arms 35 and 36 are bent over as indicated by 39 to engage 15 a disc 40 between which and the bottom 33 of the cup, is positioned a plate 41, two surfaces of which are engaged by discs 42 of friction material such as cork. The members 33 to 42 inclusive, comprise the clutch members, within cup member 30.

The shaft 18 is positioned within a hollow spindle 43 on which the die 17 is securely fastened. The lower end of the spindle 43 is formed so as to provide a pair of keys 44 25 which drivingly engage cooperating grooves in the plate 41, thereby giving a driving connection between the plate 41 and the die. By this arrangement it will be observed that the die structure may be easily withdrawn 30 and a die bearing a different indicia, quickly inserted in place.

The shaft 18 is hollow and carries within the hollow portion, a pin 45 and a spring 46, the tension of which may be adjusted by an 35 adjusting screw 47 which is held in adjusted position by a lock nut 48, 49 being a bushing carried in the member 20 and supporting the upper end of the shaft 18.

It will be apparent from what has been 40 said and by reference to Figure 2, that adjusting screw 47 regulates the tension of the clutch members through the medium of the pin 37, the arms 35 and 36, the disc 40, plate 41, and friction members 42. The spindle 43 45 carries a gear 50 which is used to operate a register or counter for registering or counting the number of pieces of mail which are stamped by the die.

Positioned over the cup member 30, is a 50 casing 51, which is also in the form of a cup-shaped member having a rim portion 52 adjacent the base part of the cup, formed so as to provide a pulley surface for continuously engaging the pressure roller 23. The casing 55 51 as shown in Figures 2, 3, and 4, is fastened to the cup member 30 by a push fit, but any other satisfactory attachment means may be provided, such as is indicated in Figure 5, where the bottom of the cup member 30 is bored out and carries a pin 53 and a spring 54, which tends normally to push the pin 53 outward into a hole in the casing 51.

The pin 53 may be released from engaging the casing 51 by another pin 55 operating in 60 a slot in the bottom of the member 30.

Heretofore it has been necessary to provide a stop and suitable adjusting means for the pressure roller 23, but in our present arrangement this roller is being pressed continually against the pulley surface 52 of the clutch cover which acts as a continual stop for the pressure roller 23 and with it, serves to catch the forward end of the letters or mail matter as these pieces are passed forward by the feed rollers 10 and 11, and since the combination 70 clutch cover and pulley and pressure roller are in continual rotation, material assistance is given toward quickly and accurately passing the mail matter by the die.

We believe we are the first to discover the advantages of making the clutch cover serve additional functions than that of merely as a cover, by utilizing it as a stop for the pressure roller and also forming with the pressure roller a supplemental pair of feed rollers; also we cause the pressure roller to act in a 80 dual function, first as a pressure roller for the die, and secondly as a feed roller in association with a clutch member. We desire therefore, to cover this arrangement in its broadest 90 terms.

Having thus described our invention, what we claim is:

1. For an apparatus of the class described 95 having a rotatable pressure roller and a printing die for cooperation with the pressure roller; a driving member and clutch elements forming a driving connection between the driving member and the die and a casing for said clutch elements and rotatable therewith; said casing having at least a part 100 of its outer surface formed into a pulley surface for engagement with said pressure roller for the purposes described.

2. For an apparatus of the class described 105 having a rotatable pressure roller and a printing die for cooperation with the pressure roller; a driving member and clutch elements forming a driving connection between the driving member and the die and a casing for said clutch elements and rotatable therewith, said casing having at least a part 110 of its outer surface formed into a pulley surface having substantially the same diameter as the die and in continuous engagement with said pressure roller for the purposes described.

3. For an apparatus of the class described 120 having a rotatable pressure roller and a printing die for cooperation with the pressure roller; a driving member and clutch elements forming a driving connection between the driving member and the die, means for utilizing the pressure roller also as a feed roller, said means consisting of a casing for said 125 clutch elements having at least a part of its outer surface formed to engage the pressure roller thereby forming with the same a pair of feed rollers to assist in moving the mail matter by the die.

4. For an apparatus of the class described having a rotatable pressure roller and a printing die for cooperation with the pressure roller; a driving member and clutch elements forming a driving connection between the driving member and the die, means for obtaining a supplemental feed roller having the same rotatable axis as the die and to cooperate with the pressure roller to form a feed right at the die, said means consisting of a casing fitting over and rotatably held to a driving element of said clutch, the casing having at least a part of its surface formed into a pulley for continuous engagement with the pressure roller. 70
5. For an apparatus of the class described having a rotatable pressure roller and a printing die for cooperation with the pressure roller; a driving member and clutch elements forming a driving connection between the driving member and the die, means for obtaining a supplemental guide and feeding action having its operative surface in the same plane as the cooperating surfaces between the die and pressure roller, said means including a casing for said clutch elements, the casing having a driving connection with one of the driving elements of the clutch and further having at least a part of its outer surface substantially the same diameter as the die and formed to engage the pressure roller below that part engaged by the die. 75
6. For an apparatus of the class described having a rotatable pressure roller and a printing die for cooperation with the pressure roller; a driving member and clutch elements forming a driving connection between the driving member and the die, means for obtaining a dual function from the pressure roller and the clutch, said means consisting in providing the clutch with a cup-shaped casing having a driving engagement with a driving element of the clutch and having a pulley surface on at least a part of its outer periphery for engagement with the lower part of the pressure roller to thereby form a pair of extra feed rollers. 80
7. For an apparatus of the class described having a rotatable pressure roller and a printing die for cooperation with the pressure roller; a driving member and clutch elements forming a driving connection between the driving member and the die, and a casing for said clutch elements, said casing having a releasable driving connection with a driving element of the clutch and also having at least a part of its outer periphery formed into a pulley surface to engage the pressure roller thereby establishing a pair of supplemental guide and feed rollers having their cooperative surfaces substantially in the same plane as the cooperative surfaces between the pressure roller and die. 85
8. For an apparatus of the class described having a rotatable pressure roller and a printing die for cooperation with the pressure roller; a driving member and clutch elements forming a driving connection between the driving member and the die, said clutch elements including two cup-shaped members one within the other, the inner one having certain other clutch elements housed within it, while the outer one is operatively fastened to the inner cup and has at least a part of its surface substantially the diameter of the die and arranged to engage the lower part of said pressure roller forming therewith a supplemental pair of feed rollers for the purposes described. 90
9. For an apparatus of the class described having a rotatable pressure roller and a printing die for cooperation with the pressure roller; a driving member and clutch elements forming a driving connection between the driving member, and the die, and a casing for said clutch elements having a driving connection with a driving element of the clutch, said casing having at least a part in contact with the pressure roller and acting as a stop therefor as well as forming therewith a supplemental pair of feed rollers. 95
10. For an apparatus of the class described having a rotatable pressure roller and a printing die for cooperation with the pressure roller; a driving shaft, a hollow spindle positioned over the shaft and carrying the die, clutch elements forming a driving connection between the driving shaft and said die spindle, said driving connection including; a clutch plate having at least one keyway therein and a key formed on the end of said die spindle to fit said keyway whereby the die may be readily removed from the shaft; said clutch elements all being positioned around the shaft below the die, and a casing for enclosing all of said clutch elements, said casing having at least a part of its outer surface formed into a pulley surface for engagement with said pressure roller for the purposes described. 100
11. For an apparatus of the class described having a rotatable pressure roller and a printing die for cooperation with the pressure roller; a driving shaft, a hollow spindle positioned over the shaft and carrying the die, said spindle having one end extending below the die and terminating in slidable locking means, clutch elements forming a driving connection between the driving shaft and said die spindle, said driving connection including; a clutch plate having means for completing a slidable lock with said spindle slidable locking means whereby the die and its spindle may be readily removed from the shaft and clutch elements, said clutch elements all being positioned below the die, and a casing for enclosing all of said clutch elements, said casing having at least a part of its outer surface formed into a pulley sur- 105

face for engagement with said pressure roller for the purposes described.

12. In an apparatus of the class described, a driving shaft, a hollow spindle positioned over said shaft for easy removal therefrom, a die mounted on said spindle for rotation therewith, said spindle extending below the die and terminating in slidable locking means, a clutch plate fitting over and cooperating with said locking means to be rotated thereby, friction elements on both sides of said clutch plate, means including parts carried by and rotatable with the shaft for applying pressure to said friction elements, and a casing enclosing all of said clutch parts, said casing having at least a part of its outer surface formed into a pulley surface, and a pressure roller having at least a part of its outer surface normally held in engagement with said casing pulley surface.

In testimony whereof, we affix our signatures.

LAWRENCE J. ZAHN.
